UNITED STATES PATENT OFFICE

2,063,675

MEANS FOR STRIPPING INGOTS

Ossian Hively, Alliance, Ohio, assignor to The
Morgan Engineering Company, Alliance, Ohio

Application January 7, 1935, Serial No. 768

8 Claims. (Cl. 22—95)

This invention relates to a method and means for stripping an ingot from a "big-end-up" mold and the primary purpose of the invention is to improve mold supporting means so that stripping may be accomplished by stripper cranes of known construction.

One company in the United States has been for many years a leading manufacturer of stripper cranes and such cranes were originally designed to strip "big-end-down" molds which are still used very largely in the trade in casting ingots. With this type of mold, the stripper links engage the ears of the mold, while the stripper ram is inserted through the top of the mold, holding the ingot down on the stool while the links pull the mold off the ingot. The mold is then raised high enough to clear the ingot and is placed upon an empty car standing ready to receive it, on a track next to and parallel to that on which the stripped ingot stands.

The constant endeavor of the steel industry has been to reduce the amount of discard from the top of the ingot. This discard is due to pipes, blow-holes, segregations and crystallizations which take place in the metal in the ingot during the solidification of the liquid metal.

Various methods have been used to reduce the loss from discard, among which is the so-called hot top mold or the big end up mold. The big-end-up mold, of course, cannot be stripped in the same manner as has been done with the old type of mold for the reason that the ingot must be removed through the top of the mold instead of through the bottom opening.

One method of preventing undue loss in the ingot discard, has been to place a ring of refractory material, such as baked clay, surmounting the ingot mold. This non-conducting ring kept the steel in a molten state so that it cooled slowly toward the center of the ingot and thus increased the percentage of sound steel in the ingot. This type of ingot mold is stripped by first breaking off the insulating ring, then gripping the protruding sink head with crane tongs and pulling the ingot out of the mold, while at the same time holding the mold down by means of a pair of links resting on the top of the mold.

A further demand for clean steel, especially in such refined industries as the automotive plants, has of late increased the production of what is known in the trade as "rimming steel" which is so effervescent in character when liquid, that it must be cast in flush top molds, which are also of the big-end-up type.

55 A purpose of this invention is to provide a

means for stripping molds of this latter type by the use of already existing overhead travelling crane type of electric strippers, of which there are many in use representing an investment of many millions of dollars.

Another object is to use already existing ingot cars.

Another purpose is to provide a means of stripping this type of molds, retaining the molds on the cars while pouring the ingot and stripping same.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a vertical cross sectional view of the improved stripping stool with the mold in the position it occupies while the metal is being poured and showing a portion of the stripper mechanism ready to strip the ingot from the mold.

Fig. 2 is a similar view of the stool, mold and ingot after the ingot has been loosened from the mold.

Fig. 3 is a vertical sectional view of a portion of a known type of stripper crane.

Figs. 4, 5 and 6, are vertical sectional views respectively of modifications of the stool.

Referring to Figs. 1 to 3 inclusive, of the drawings, 3 designates the improved stripping stool designed to be carried on a conventional ingot car 4. The stool forms a frame 5 and is provided at its central portion with a rigidly connected, upstanding stem 6 forming a stripper ram on which the bottom of the mold is slideable; such ram being secured in position by any suitable means such as a nut 7. Bell crank levers 8 are positioned vertically on the frame and mounted for swinging movement on horizontal trunnions 9 carried by the frame. Each lever has a projecting ear 10 for use in swinging the lower portions of the levers away from the ram 6. Each lever also has a step 11 and these steps normally support the mold 12 while the ingot is being poured. Springs 13 on the frame, extend into pockets 14 in the lower ends 50 of the levers for yieldingly holding them in position to support the mold, and keeper plates 15 act to hold the springs in place.

The stripper crane mechanism may be of conventional construction and include apertured

links 16 which swing on horizontal trunnions 16a. At 17 the crane stripper may be provided with an inverted cup or horseshoe-shaped member, and this cup will be forced downwardly simultaneously with the lifting of the links 16 by any suitable means, such as a double acting screw 18. A suitable type of crane stripper is shown in the patent to Bigler and Kloos 1,807,275, May 26, 1931.

10 In using such mechanism, the ingot 19 is cast while the mold is in the position shown in Fig. 1, and when it is desired to strip the ingot from the mold, the crane links 16 are brought into engagement with the ears 10 of the bell crank levers, 15 and the member 17 is brought to bear on the top of the mold, whereupon the crane operator causes the double acting screw 18 to revolve in the proper direction so that an upward movement on the link 16 and a downward movement on the 20 cup 17 are simultaneously exerted. This pulls the steps 11 from beneath the mold and at the same time the latter is forced downwardly by the cup 17. During the downward movement of the mold, the latter is supported in its original position by the ram 6 and after such movement, the 25 stool, mold and ingot will assume the positions shown in Fig. 2. The ingot can then be gripped at its upper end by means of crane tongs and lifted free of the mold.

30 To place the mold in its initial position to receive a subsequent pouring, the links 16 are brought into engagement with lugs 20 on the upper end of the mold and as the links are moved upwardly they elevate the mold, until the springs 35 13 snap the steps 11 underneath the mold again, whereupon the mold and other parts will be ready for the next pouring.

In the modification of the stool shown in Fig. 4, it will be observed that I have eliminated the 40 springs and substituted interlocking bell cranks, although the general operation is the same as with the spring. This modification was designed to overcome any objection that might be raised as to having the springs in a locality where there is 45 a great deal of heat. Referring to this modification, 3a designates a cup-shaped stool having a stationary ram 6a which projects upwardly from the central portion of the bottom of the stool for the purpose of supporting the ingot while 50 the mold is moved downwardly. During the pouring operation, the mold is supported by steps 11a on a first pair of bell crank levers 8a pivotally mounted on trunnions 9a supported by the stool. These levers cooperate with a second pair of 55 locking bell crank levers 8b pivoted on horizontal trunnions 9b supported by the stool. The arms 11b of the second levers act to limit the movement of the levers 8a while they are supporting the mold, and arms 10a of the upper levers form ears 60 to be engaged by the links 16 of the stripping mechanism shown in Fig. 1. Obviously when the links pull upwardly on the arms 10a, they release the levers 8a and allow the mold to move downwardly away from the ingot while the latter 65 is supported by the ram 6a.

In case objection should be made to the dropping of the mold by the structures shown in Figs. 1 to 4 inclusive, from its normal or pouring position to the upper surface of the stool, I may 70 employ stools of the type shown in Figs. 5 and 6. In these embodiments the mold in pouring position rests on steps and the stripping is not accomplished by allowing the mold to drop, but is brought about by pushing the mold downwardly 75 until it rests on the stool; the springs in such

case having sufficient strength to sustain the weight of the mold and ingot in the initial or normal position and also being susceptible of compression to allow the levers to be pushed away enough to permit the mold to pass by its lower 5 position. However, during such movement, the springs through the levers exert a braking action on the mold which prevents it from dropping. In reference to the specific details of such stools, it will be noted in Fig. 5 that the cup-shaped stool 3c is provided with ears 10c designed to be engaged by the links 16 of the crane stripper, and the bell crank levers 8c are mounted on trunnions 9c within the stool. Each lever has a mold-supporting step 11c on one arm and 10 its other arm 14c engages a vertical coil spring 13c arranged within the stool. Of course, this stool also has a stationary ram 6c.

Instead of employing bell crank levers, I may 20 use single arm levers 8d as illustrated in Fig. 6. These levers are mounted at their upper ends on trunnions 9d supported by the stool and their lower ends are engaged by coil springs 13d which 25 act to force the levers toward the stationary ram 6d. Each lever has a mold-supporting step 11d and the stool has ears 10d to be engaged by the 30 links 16.

With the forms of stools shown in Figs. 5 and 6, pressure on the mold, while it is supported by the steps, will cause the levers to recede while they 35 are braked by the springs, and, of course, the stool can be lifted while the mold is being forced downwardly, although this is not absolutely necessary.

While I have disclosed what I now consider to 35 be preferred embodiments of my apparatus and ways of practicing the method, it will be understood that changes may be made in the details disclosed without departing from the spirit of the 40 invention as expressed in the claims.

What I claim and desire to secure by Letters 45 Patent is:

1. An ingot stripping stool of the character described comprising a frame having a top opening of sufficient size to receive a conventional ingot mold, bellcranks journaled in the frame and having suspended arms provided with seats to support an ingot mold, means for holding the bellcranks in engagement with the mold, lugs on said bellcranks projecting from opposite sides of the 50 frame and adapted to be engaged by crane links for swinging the bellcranks out of engagement with the mold, and a ram rigidly secured to the bottom portion of the stool and projecting upwardly in the frame to contact the lower surface of an ingot within said mold.

2. In an apparatus of the character described, an ingot stripping stool comprising a frame having centrally disposed upstanding substantially 60 stationary ram, levers pivotally mounted on horizontal axes and having steps at their lower end portions to support a mold, means for yieldingly urging the stepped portions of the levers toward said ram, and means on the levers to facilitate 65 movement of the step portions away from the ram.

3. An ingot stripping stool comprising a frame having an upstanding substantially centrally disposed ram projecting from its bottom, levers pivotally mounted on the frame for movement about horizontal axes and having mold supporting portions, yielding means for moving the mold supporting portions of the levers toward said ram, and means on the levers to facilitate movement 70 75 75

- of said mold supporting portions away from said ram.
4. An ingot stripping stool comprising a frame having a bottom and upstanding portion, a stationary ram projecting upwardly from the central portion of said bottom, bellcrank levers having their upper end portions pivotally mounted for movement about horizontal axes arranged on the upstanding portion of said frame, mold supporting steps provided on the lower portions of said levers, yielding means for moving said steps toward said ram, and ears projecting from the upper end portions of said levers to facilitate movement of said steps away from said ram.
- 10 5. Ingot stripping mechanism comprising a stool having an upstanding substantially stationary ram, said ram being adapted to extend slidably through the bottom of a mold, levers pivotally mounted on the stool and provided with steps to support the mold, yielding means for moving the step portions of the levers toward the ram, said levers having projecting ears, crane links engageable with said ears for moving the step portions of the levers away from the ram, a member engageable with the mold, and means for moving the links and member in opposite directions for swinging the levers out of mold supporting position and for moving the mold downwardly.
- 20 6. In ingot stripping mechanism of the class described, a stool, levers pivotally supported by the stool and provided with means for supporting the mold on the stool, releasable means for holding the levers in mold-supporting position, and a ram projecting upwardly from the bottom por-
- tion of the stool and adapted to extend through the bottom of said mold for supporting an ingot within the mold while the mold is moved relatively to said stool, said releasable means including springs for yieldingly urging the levers toward 5 mold-supporting position.
7. In ingot stripping mechanism of the class described, a stool, levers pivotally supported by the stool and provided with means for supporting the mold on the stool, releasable means for holding the levers in mold-supporting position, and a ram projecting upwardly from the bottom portion of the stool and adapted to extend through the bottom of said mold for supporting an ingot within the mold while the mold is moved relatively to said stool, said releasable means including bell crank levers engageable with said levers for limiting the movement of the levers in directions away from said ram.
- 10 8. In an ingot stripper stool of the character described, a hollow frame having a top opening of sufficient size to receive a conventional ingot-stripping mold, supports journaled in the frame and adapted to support an ingot mold while the latter contains an ingot, a stripping ram rigidly 25 secured to the bottom of the frame and projecting upwardly to contact the lower surface of an ingot within the mold, and means projecting from opposite sides of the frame and adapted to be engaged by the links of a stripping crane for releasing the supports from the mold to allow relative axial movement of the ram and mold.
